UNITED STATES PATENT OFFICE.

THACHER JENNEY, OF LEXINGTON, MASSACHUSETTS, AND HARRY G. MINER, OF LOUISVILLE, KENTUCKY, ASSIGNORS TO AMERICAN SODA FOUNTAIN COMPANY, A CORPORATION OF MASSACHUSETTS.

REFRIGERATED COMPARTMENT AND COVER THEREFOR.

Application filed April 20, 1925. Serial No. 24,390.

This invention relates to refrigerated compartments or cabinets adapted to contain ice cream and the like material and is especially adapted although not necessarily limited to 5 soda fountain use.

One of the objects of this invention is the provision of a top or cover for a refrigerated compartment and so constructed that it is relatively free from projections or crevices 10 about or into which dirt may collect and which renders difficult the cleaning of the cover.

A further object of the invention is the provision of a top or cover having an opening therethrough by which access is obtained 15 to the contents of the refrigerated compartment and with means to prevent fluid or liquid which may have collected on the top from entering the opening, with the attendant danger of contaminating the contents of the compartment.

A further object of the invention is to provide a cover or lid for the opening in the compartment top with hinged means for the 25 lid disposed and concealed beneath the top and operating through the opening in the top.

A further object of the invention is the provision of a lid for the opening in the compartment top so arranged that any liquid 30 which may collect on the lid is carried away from the opening and deposited upon the top when the lid is raised whereby to prevent such liquid from entering the compartment 35 through the opening.

A yet further object of the invention is the provision of a lid for the top opening which is so constructed and arranged that it offers material resistance to the flow of heat there- 40 through whereby to improve the refrigerating efficiency of the compartment with which it may be associated.

A further object is generally to improve the construction of top covers for refriger- 45 ated compartments.

Fig. 1 is a perspective detail illustrating the application of the invention to a refrigerated compartment.

Fig. 2 is a side elevation of the compartment top embodying the invention.

Fig. 3 is a reverse plan view of Fig. 2.

Fig. 4 is a cross sectional view of the compartment top with the cover in raised position.

Fig. 5 is a sectional detail illustrating the 55 construction of the top at the opening therein.

Fig. 6 is a sectional detail illustrating more particularly the construction of the 60 cover.

Fig. 7 is an exploded view of some of the top components.

This invention is herein shown applied to a refrigerated compartment or cabinet 10 adapted to contain an open top can 12 or the 65 like which may contain ice cream; and the top-cover embodying the invention is adapted removably to close the open top of the compartment. The top-cover embodying the invention comprises a more or less 70 flat and rectangular metal top plate 14, which plate is formed with a depending rear wall 16. The top plate is also formed with a circular opening 18 in the middle thereof.

A flat rectangular bottom plate 20 cooper- 75 ates with the top plate and said bottom plate is formed or provided with upstanding front and side walls 21 and 22 respectively. The bottom plate is placed with the edges of its 80 upstanding walls against the under face of the top plate and with the depending wall 16 of the top plate against the un-reflexed rear edge of the bottom plate so that a confined and heat-insulating space 25 is formed 85 between the two plates. Said plates may be secured together in the aforesaid relation in any suitable manner as by solder. Preferably the dimensions of the top plate are such that said plate overlaps the bottom plate on 90 three sides and thereby forms a shelf by which the top-cover is supported over and in closing relation with the top opening of the compartment. Preferably suitable insulating material, not shown, is contained in the 95 confined space between the top and bottom plates whereby to insulate the top-cover against the passage of heat into the compartment.

The bottom plate 20 is formed with a circular aperture 24 therein which is disposed 100 in alignment with the circular aperture 18 in the top plate. A more or less rectangular aperture 26 is also formed in said bottom plate adjacent the rear edge thereof and in communication with said aperture 24. Means are provided to seal the space between the top and bottom plates at the apertures 105 whereby to improve the heat insulating

properties of the top and also to prevent water or dirt from entering the confined space. Said sealing means includes a more or less circular collar 28 which is disposed 5 within the openings 18 and 24 of the top and bottom plates and preferably extends in opposite directions beyond said openings. Said collar is provided with proximate ends 30 adjacent the edges of the slot 26 in the bottom plate. The upper edge of said collar is reflexed to form an outstanding flange 32 which overlies and is disposed against the top face of the top plate 14. Preferably said flange is terminated short of the ends 15 30 of the collar. The lower edge of said collar also is reflexed to form an outstanding flange 34 which overlies and is disposed against the lower face of the bottom plate 20. Said flanges are preferably soldered to 20 the top and bottom plates whereby to secure said collar to said plates and also seal the connection therebetween.

The sealing means for the recess or slot 26 includes the member 36, which member is 25 shaped to conform with the outline of said recess 26 and is provided with outstanding flanges 38 which are soldered to the bottom plate 20. The top edge of said member is soldered to the lower face of the top plate 30 14; and said member, in cooperation with said collar 28, provides a complete seal for said confined space between the top and bottom plates at the openings therein.

It is one of the objects of this invention to 35 provide a construction which will prevent any liquid which may rest upon the top plate 14 from entering the aperture therein. In accordance with this object, I provide an 40 annular ring 40 which is carried by the top-cover and surrounds the opening. Said ring is of substantial height and is or may be provided with a flat upper face 42 against which a lid hereinafter to be described is adapted to seat. Said ring is formed or 45 provided with a radial outstanding flange 44 which is adapted to overlie the top plate 14; and said flange is formed with an annular groove 46 in its lower face in which the collar-flange 32 is received. Said recess 50 preferably is deeper than the height of the flange so that the bottom and outer edge 48 of said flange may bear snugly against the top plate. Preferably the joint between the flange and the top plate is filled in with 55 solder whereby to seal the joint and fill in any crevices in which dirt may otherwise collect. Said annular ring 40 is also provided with an axially extended flange 50 which depends into the collar 28 and overlies the side wall thereof. The joint between said flange and the collar also is preferably filled in with solder.

The opening through the collar and ring 60 is adapted removably to be closed by a lid 65 which in accordance with this invention is

so constructed and arranged that it offers material resistance to the transfer of heat therethrough. To this end the lid is provided with a circular bottom plate 52 which is internally dished or concaved and is 70 formed with the radially extended peripheral edge portion 54. A flat circular top plate 56 is disposed over said dished bottom plate and the peripheral edge portion of said top plate is reflexed over the peripheral edge 54 of the bottom plate whereby to unite the two plates together rigidly and form a substantially air tight space 58 between the two plates. Preferably a body 60 of a heat insulating packing material, as 75 soft rubber, for instance, is disposed about the edge 54 of the bottom plate and interposed between the bottom plate and the top plate at the joint therebetween so that the two plates are maintained out of direct thermal contact with each other whereby the flow of heat between the two plates is further retarded.

The lid thus described is adapted to rest upon the flat face 42 of the ring 40 and to extend outwardly beyond said ring as illustrated in Fig. 2, whereby to shield the joint between said lid and ring.

The lid is hinged to the top-cover by hinge members which are disposed beneath the top so that the top is free and clear from obstructions on or about which dirt may collect. One of the hinged members includes a flat plate 62 which is disposed within the recess 64 provided by the member 36 and is secured to the lower face of the top plate 14 by suitable means as rivets 65. Said member is formed or provided with a depending ear 66 through which a pivot pin 68 is extended loosely. A hinge-bracket 70 is fixed 1 to the lower face of the bottom plate 52 of the cover by suitable means as screws 72. Said bracket is formed or provided with a pair of spaced and laterally extended arms 74 which extend through the opening in the 11 top-cover and terminate in upwardly extended end portions 75 which are disposed on opposite sides of said projection 66 and are secured to said pin 68. The construction is such that the lid may be raised into an 115 approximately vertical position and will remain in such position until displaced therefrom. Inasmuch as the cover peripherally overlaps the ring 40 any moisture which collects on the top of the lid will run off and 120 onto the top plate without entering the top opening when the lid is raised.

We claim:

1. A top-cover for a refrigerated compartment including a top-plate having a 125 downwardly reflexed rear wall, a bottom-plate disposed beneath and spaced from said top-plate and having upwardly reflexed front and side walls, said reflexed walls of both plates cooperating to enclose the space 130

- between said plates, said plates having aligned apertures therein, a collar extended through said openings and having outstanding flanges which overlie said top and bottom walls, and a ring disposed upon said top plate about said collar and having an outstanding flange formed with a groove in the lower face of the flange in which the upper collar-flange is received and enclosed. 5
- 10 2. A top-cover for a refrigerated compartment including a top-plate having a downwardly reflexed rear wall, a bottom-plate disposed beneath and spaced from said top-plate and having upwardly reflexed front and side walls, said reflexed walls of both plates cooperating to enclose the space between said plates, said plates having
- aligned apertures therein, a collar extended through said openings and having outstanding flanges which overlie said top and bottom walls, a ring disposed upon said top plate about said collar and having an outstanding flange formed with a groove in the lower face of the flange in which the upper collar-flange is received and enclosed, a lid 20 disposed to rest upon said ring and cover the opening therein, and a hinged connection for said lid extended through said ring and collar and fixed to the lower face of the top-cover. 25
- 30 In testimony whereof, we have signed our names to this specification.

THACHER JENNEY.
HARRY G. MINER.
